INVENTOR

Augustine F. Littlefield
By his Attorney,
Nelson W. Howard

UNITED STATES PATENT OFFICE.

AUGUSTINE F. LITTLEFIELD, OF LYNN, MASSACHUSETTS, ASSIGNOR TO UNITED SHOE MACHINERY CORPORATION, OF PATERSON, NEW JERSEY, A CORPORATION OF NEW JERSEY.

RIGID-BOTTOM COLLAPSIBLE LAST.

1,359,611.

Specification of Letters Patent. Patented Nov. 23, 1920.

Original application filed April 16, 1919, Serial No. 290,441. Divided and this application filed March 23, 1920. Serial No. 368,125.

To all whom it may concern:

Be it known that I, AUGUSTINE F. LITTLEFIELD, a citizen of the United States, residing at Lynn, in the county of Essex and 5 State of Massachusetts, have invented certain Improvements in Rigid-Bottom Collapsible Lasts, of which the following description, in connection with the accompanying drawings, is a specification, like 10 reference characters on the drawings indicating like parts in the several figures.

This invention relates to boot and shoe lasts and in particular to collapsible lasts, and this application is a division of my 15 application Ser. No. 290,441, filed April 16, 1919.

In some methods or lines of boot and shoemaking, it is desirable to employ lasts which are permanently rigid against flexure or vertical bending moments. If a 20 block last is employed and the shoe upper is conformed closely thereto, removal of the last without injury to the shoe is laborious and difficult and sometimes practically impossible. Hence, it is common to use so-called collapsible or hinged lasts, the heel 25 portions of which can be moved to give sufficient relief to permit ready withdrawal of the last from the shoe, thus sacrificing permanent rigidity.

A particular object of the present invention is to provide a last which, for all classes of work, will always present a rigid or inflexible sole surface portion from toe to heel, but which is capable of being laterally collapsed to permit ready withdrawal from the shoe. In attaining the object I provide the last with a laterally collapsible heel portion the sole surface of which is rigid 40 against flexure or vertical bending moments.

I have illustrated an embodiment of my invention in which the last, although having an inflexible sole surface from end to end, may still be termed a collapsible or 45 hinged last. The hinged structure, however, is such, that instead of flexing the whole heel part on an axis transverse of the last so as to shorten the last as a whole as is common with hinged lasts in general, the lateral 50 thickness or width of the last at the heel may be reduced to allow the heel of the shoe to lengthen a little by virtue of not being filled laterally.

An important feature of the invention 55 consists in a last having a rigid heel section and a heel section movable upwardly, preferably diagonally and parallel to its outside surface, to collapse the heel part as a whole.

These and other features of the invention 60 comprising certain combinations and arrangements of parts will be understood from the following description of a preferred embodiment thereof selected for purposes of illustration and shown in the accompanying 65 drawings in which,

Figures 1 and 2 of the drawings are, respectively, a side elevation and plan view, a portion being broken out and in section in Fig. 1.

Fig. 3 is an end elevation of the forepart 70 of the last from which the heel part has been removed.

Fig. 4 represents a section on line 4 of Fig. 2.

Fig. 5 is a sectional view similar to Fig. 4 but showing the parts in different relative positions, the plane of section through each of the two heel parts being the same as in Fig. 4, although one part in Fig. 5 has 80 been swung up to substantially the dotted line position of Fig. 1.

Fig. 6 is a side elevation of the rigid heel section of the last.

Fig. 7 is a perspective view of a tool or 85 implement which may be employed for unlocking the two heel sections of the last so that one may be swung as hereinafter described.

The forepart 40 of the last is provided 90 with a recess 41 (Fig. 3) which receives the web 42 of the rigid heel section 43, the connection being rendered permanent and rigid by means of transverse pins 44. The rigid heel section 43 is preferably of metal and 95 may be a casting. As best illustrated in Fig. 6, it is formed on its inner face with a recess 45 having an undercut portion 46 to serve as a keeper for the locking pin hereinafter described. The section 43 is 100 also formed with a rib 47 having an inclined face to form an abutment for the inclined front face of the heel section 48 pivotally connected to the section 43 by a pin 49 which is transversely inclined substantially 105 as indicated by the dotted lines in Fig. 4.

The contracting or sliding faces of the sections 43, 48 are, of course, in a plane perpendicular to the axis of pivot pin 49, and are preferably substantially parallel to the outside lateral face of the section 48.

Fixed in a recess in the section 48 is a thimble 50 having a band 51 rotatably mounted upon its lower end, the inner wall of the thimble 50 having a vertical groove 52 terminating at its lower end in a lateral groove 53. A pin 54 is rigidly mounted in the band 51, the outer end of said pin being adapted to engage the groove 46 (Fig. 4) and the inner end of the pin projecting 15 through a slot 54' in the thimble 50 into the interior thereof.

A tool 55 which may be a jack pin is provided with a recess 56 in one side of its lower end, and has a pin 57 projecting from its 20 side (Fig. 7).

Mounted in an inclined recess in the section 43 is a detent 58 the front end of which is preferably rounded, said detent being pressed outwardly by a spring 59 so that the detent may engage either one of two keeper recesses 60 in the inner face of section 48 (Fig. 4).

When the last is in the condition shown in Fig. 2 and by full lines in Fig. 1, it is 30 adapted to be used to enable any of the ordinary shoe operations to be performed upon it. As a whole, this last is permanently rigid against flexure. When it is to be removed from the shoe, such a tool as indicated in Fig. 7 is inserted in the thimble 50, its pin 57 sliding down the groove 52. At the same time, its recess 56 engages the inner end of the locking pin 54. Then, by turning the tool, the pin 57 passes into the extension 35 53 of the vertical groove 52 and the recess 56 of said tool acts upon the pin 54 to rotate it and its carrying band 51 until the outer end of the pin 54 which has been engaged in the keeper section 46 reaches the vertical recess 40 45 53 so that the heel section 48 can be swung up on its pivot 49 as by means of forward pressure exerted against the tool 55 which is now locked in the thimble 50 by reason of its pin 57 being engaged with the lateral extension 50 53 of the groove in the thimble. This shifting of the section 48 is readily effected since the spring 59 is not of sufficient strength to cause the detent 58 to rigidly remain in the upper recess 60. When the 55 section 48 has been swung up to the dotted line position of Fig. 1 and to the full line position of Fig. 5, the lateral thickness of the last at the heel has been diminished sufficiently to enable the heel of the shoe to 60 lengthen a little because it is not filled laterally.

This invention provides for the displacement of a longitudinally and vertically extending slice of the heel. The heel width is reduced by turning a section of the heel 65 diagonally vertically in a direction which is substantially parallel to its outside lateral surface. The lateral thickness of the heel is thus diminished to allow the heel of the shoe to lengthen sufficiently to enable the 70 last to be separated from the shoe.

Having now described my invention, I claim:—

1. A last having a heel section formed rigid with the main body of the last as regards vertical bending, and a second heel section constructed and arranged to move upwardly relatively to the first-named heel section to collapse the last.

2. A last having a heel section formed integrally with the main body of the last, and a second heel section arranged to move upwardly and laterally relatively to the first-named heel section to collapse the last.

3. A last having a rigid heel section 80 formed with an inclined side face, and a heel section pivotally connected therewith and constructed and arranged to be moved upwardly in a diagonally vertical direction substantially parallel to its outside lateral 90 surface.

4. A last having a rigid heel section provided with a laterally inclined face, a movable heel section having an inclined face 95 adapted to coöperate with the inclined face of the rigid heel section, said two heel sections having a pivotal connection the axis of which is inclined laterally of the last.

5. A last having a rigid heel section provided with a laterally inclined face, a movable heel section having an inclined face adapted to coöperate with the inclined face of the rigid heel section, said two heel sections having a pivotal connection the axis of which is inclined laterally of the last, and 100 means for locking the heel sections with their bottom surfaces in substantial alignment.

6. A last having a rigid heel section provided with a laterally inclined face, a movable heel section having an inclined face 11 adapted to coöperate with the inclined face of the rigid heel section, said two heel sections having a pivotal connection the axis of which is inclined laterally of the last, the rigid heel section having a keeper recess and the movable heel section having a locking pin adapted to engage said recess and to be freed therefrom.

In testimony whereof I have signed my name to this specification.

AUGUSTINE F. LITTLEFIELD.
